PORTABLE CHAIR

Carl E. Bowles, Lewiston, Idaho, assignor of
fifteen per cent to Vincent L. Neal, and thirty-
four per cent to Earl Sumpter, both of Lewis-
ton, Idaho

Application June 10, 1939, Serial No. 278,569

8 Claims. (Cl. 155—133)

This invention relates to a portable chair de-
signed primarily for detachable connection to
the seat boards of stadiums, stationary and fold-
able grandstands, reviewing stands, bleachers
and supported planks, but it is to be understood
that a portable chair, in accordance with this
invention is for use in any connection for which
it may be found applicable.

The invention aims to provide, in a manner
10 as hereinafter set forth, a chair of the class re-
ferred to including an upstanding substantially
rigid supporting element for mounting on and
for detachable connection to a support, such as
a seat board, and a bendable element connected
15 to the said other element and providing the chair
with a padded seat and a bendable back function-
ing to prevent discomfiture to the user when
the chair is attached to the seat board and which
would not be the case if the seat board was em-
20 ployed without the chair.

The invention further aims to provide, in a
manner as hereinafter set forth a chair of the
class referred to including a substantially rigid
frame and bendable means anchored at its ends
25 to the ends of the frame for taking up the strain
of the weight of the occupant of the chair length-
wise of the frame thereby tending to maintain
the chair in position when the latter is connected
to a seat board.

The invention further aims to provide, in a
manner as hereinafter set forth a chair of the
class referred to including a bendable element
providing a seat and a back, a supporting frame
for and to which said element is connected, and
35 said frame and element being so constructed that
the element is capable of being expeditiously re-
moved from the frame for laundering it when
occasion requires.

The invention further aims to provide, in a
manner as hereinafter set forth, a chair for the
purpose referred to including an upstanding
angle shaped frame open at one end, means ar-
ranged within said open end to prevent the sides
45 of the frame from moving towards each other
and means correlated with the said other means
to prevent the spreading apart of the sides of
the frame.

The invention further aims to provide, in a
manner as hereinafter set forth, a chair for the
purpose referred to which is simple in its con-
struction and arrangement, strong, durable, com-
pact, affording a maximum of comfort to the
user, readily assembled, conveniently attached in
upstanding position relative to a support there-
55 for, thoroughly efficient in the use intended

therefor, readily portable when desired, com-
paratively light in weight, quickly assembled and
disassembled when occasion requires, and com-
paratively inexpensive to set up.

Embodying the aims aforesaid and others which
may hereinafter appear, the invention consists
of the novel construction, combination and ar-
rangement of parts as will be more specifically
described and as illustrated in the accompany-
ing drawing, wherein is shown an embodiment of
the invention, but it is to be understood that
changes, variations and modifications may be
resorted to which fall within the scope of the in-
vention as claimed.

In the drawing:

Figure 1 is a front elevation of a chair, in ac-
cordance with this invention assembled for use,

Figure 2 is a view looking towards one side of
the chair and with the chair shown partly in
elevation, broken away and partly in length-
wise section,

Figure 3 is a top plan view, upon an enlarged
scale illustrating a portion of the seat of the
chair and a portion of the side rails of the latter,

Figure 4 is a section on line 4—4, Figure 2 upon
an enlarged scale, and

Figure 5 is a section on line 5—5, Figure 3.

The chair includes a substantially rigid frame-
like supporting element 1 formed from a length
of metal stock, preferably tubular and which is
bent to provide the element 1 with a base 2, and
an upstanding back 3 disposed at an angle with
respect to the rear or inner end of the base 2.
The stock from which the element 1 is con-
structed will be of any desirable weight to en-
able the convenient transporting of the chair
from point to point by the user. The base 2
consists of a pair of spaced parallel horizontally
disposed parts 4 of the stock and are open at
35 their outer ends, as at 5. Each of the parts 4
is formed diametrically thereof with an open-
ing 6 positioned in proximity to its open end 5.
The parts 4 may be termed the side rails of the
base 2. The base 2 is open at its front and rear
end. The openings 6 of one of the parts 4 align
45 with the openings 6 in the other of the said
parts 4.

The back 3 is of inverted yoke-shape and in-
clines rearwardly from its lower end through-
out with respect to the rear end of the base 2. 50
The back 3 consists of a pair of spaced parallel
upstanding parts 7 and a substantially arch-
shaped part 8 of the stock. Parts 7 are the side
rails of the back and merge at their lower ends
into the inner or rear ends of the parts 4. The 55

back 3 is open at its lower end. The part 8 forms a closed top for the back, is termed a top rail and has its ends merge into the upper ends of the parts 7.

5 The chair includes a bendable combined chair seat and chair back forming element 9 consisting of a web 10 of suitable textile material formed in a manner to provide it with an intermediate portion 11, an upper fold 12 and a lower fold 13. The said folds are arranged against the inner face of the intermediate portion 11. The latter is of materially greater length than said folds. The fold 12 is of less length than the fold 13. When element 9 is set up relative to 15 element 1 the fold 12 depends from the closed top of the back 3 and the fold 13 extends rearwardly from the open front of the base 2. The fold 12 is secured to the body of the web 10 by stitching 14 thereby providing element 9 with 20 an upper tube or hem 15 extending from one side to the other side of element 9. The fold 13 rearwardly of and in proximity to the bend from which it extends is secured to the body of the web 10 by a row of stitching 16 which forms 25 element 9 with a lower or front tube or hem 17 extending from one side edge to the other side edge of the web 10. The fold 13 in close proximity to its rear end is secured to the web 10 by a row of stitching 18 located at the bend between the base 2 and the back 3. The fold 13 30 in proximity to its side edges, between the stitching 16 and 18 is secured to the body of the web 10 by the rows of stitching 19. The fold 13 in connection with a portion of the web 10 35 and the stitching 16, 18 and 19 forms a pocket 20 in which is arranged a seat pad 21, which is anchored to the web 10 by the rows of stitching 22. That portion of the web 10 between the stitchings 14, 18 and indicated at 23 provides 40 the chair with a bendable back for the user. That portion of element 9 in which is arranged the pad 21 constitutes a seat 24 for the user. The width of element 9 is less than the width of the base 2 and the back 3 of the element 1. The 45 element 9 has its tube or hem 15 disposed in encompassing relation with respect to the part 8 of the element 1. A tubular rung 25 extends through the tube or hem 17 of the element 9 and said rung 25 is adapted to be detachably connected to the element 1 in a manner to be referred to. The part 8 and ring 25 provide for detachably connecting the element 9 to the element 1. The rung 25 not only provides means for connecting the web 10 intermediate its ends 50 to the element 1, but also constitutes a brace for the parts 4 of the base 2.

The tubular rung 25 is arranged between the parts 4 of the base 2 in proximity to the open ends of said parts 4. The ends of the rung 25 55 bear against the inner sides of the said parts 4 of the base 2 and the inner diameter of said rung 25 corresponds to the diameter of the openings 6. These latter align with the open ends of the rung 25. The latter prevents the shifting of the 60 parts 4 of the base 2 towards each other. The rung 25 is detachably connected to the parts 4 of the base 2 by an elongated bolt 26 having a head 27 at one end and peripheral threads at its other end. The bolt 26 is of a length to 65 extend through the rung 25 and the parts 4 of the base 2. The bolt 26 passes through the openings 6 in the said parts 4. The head 27 abuts against the outer side of one part 4 of the base 2. The threaded end of the bolt 26 extends beyond the outer side of the other part 4

75 of the base 2. The threaded end of the bolt 26 is provided with a holding or clamping nut 28 which, when the bolt is mounted in coupling or connecting position, bears against the outer side of one of the parts 4 of the base 2. The bolt 26 in connection with its head 27 and the nut 28 prevents the spreading of the parts 4 of the base 2.

80 The chair includes a pair of coupler elements 29 of like form for connecting the chair in an upstanding position upon the seat board or other support. Each of the elements 29 is horizontally disposed and is of yoke-like form opening inwardly. Each element 29 consists of a vertically disposed front 30, a horizontally arranged bottom 31 and a horizontally disposed top 32. The latter is formed of a circular head 33 and an inner portion 34 of circular cross section. The portion 34 is of less diameter than the head 33 whereby at the junction of the portion 34 with 85 the head 33, the top 32 is formed with a peripheral shoulder 35. The diameter of the head 33 corresponds to the outer diameter of the parts 4. The upper end of the front 30 merges into the head 33. The lower end of the front 30 merges into the outer end of the bottom 31. The front 30 and the bottom 31 are of substantially oval contour in transverse section. The cross 90 sectional length of the front 30 and the bottom 31 is greater than the diameter of the portion 34 of the top 32. The portion 34 of the top 32 is formed intermediate its ends with a diametrically disposed opening 36. The portions 34 of the elements 29 are extended into the open fronts of the parts 4 of the base 2, and when so arranged 95 the shoulders 35 abut the outer end edges of the said parts 4. The fronts 30 of the elements 29 are disposed in depending relation with respect to the parts 4 of the base 2. The bottoms 31 of the elements 29 are disposed in parallel spaced 100 relation with respect to the parts 4 of the base 2. When the portions 34 of the tops 32 are arranged in the said parts 4, the openings 36 align 105 with the openings 6 and when the bolt 26 is secured to the said parts 4 the shank of the bolt 110 extends through the openings 36 and the said portions 34 whereby the couplers 29 are secured to the base 2 of the element 1.

115 When the chair is mounted on a seat board or plank, the base 2 is positioned on the top of the latter, the fronts 30 of the couplers 29 abut the outer lengthwise edge of the seat board or plank and the bottoms 31 of the couplers 29 are arranged below and parallel to the lower face of the seat board or plank whereby the chair is 120 detachably connected to the plank in an upstanding position.

125 When the chair is connected up and used, the weight of the user, when the user inclines backwardly acts to maintain the seat in coupled relation with respect to the seat board and the element 9 takes up the strain of the weight of the occupant.

130 The element 9 is detachably secured to element 1 to permit it to be removed when occasion requires for the purpose of laundering it. When element 9 is to be connected to the element 1 the tube or hem 15 is mounted on part 8 of element 1 by sliding the tube on one of the parts 4, 135 until the tube or hem 15 is arranged on part 8 in a manner as shown in Figure 1. After element 9 has been arranged in the manner aforesaid, the rung 25 is extended through the tube or hem 17 and arranged between the parts 4 of the base 2. Prior to the coupling of the rung 140

25 to the sides 4 of element 1, the couplers 29 are arranged in position relative to the parts 4 of element 1. The rung 25 and the couplers 29 are then detachably connected to the element 1 by the bolt 26 and the nut 28.

What I claim is:

1. A portable chair comprising a frame-like supporting element having a pair of spaced parallel horizontally disposed parts providing an open front and rear base portion and an inverted yoke-shaped portion extending upwardly from the rear of the base portion and providing a skeleton back portion closed at its top and open at its bottom, a suspended bendable web arranged within said portions having a part thereof constituting the seat and another part constituting the back of the chair, said web having one of its ends encompassing and loosely and removably attached to the top of said back portion, a rung arranged within the open front of said base, said web, intermediate its ends encompassing and loosely and removably attached to said rung, couplers extending into the outer ends of said horizontal parts for detachably connecting the base of said supporting element upon a support, and means extending through said horizontal parts, couplers and rung for detachably connecting the rung, couplers and web to the base portion of said supporting element.

2. A portable chair comprising a frame-like supporting element having a pair of spaced parallel horizontally disposed parts providing an open front and rear base portion and an inverted yoke-shaped portion extending upwardly from the rear of the base portion and providing a skeleton back portion closed at its top and open at its bottom, a suspended bendable web arranged within said portions having a part thereof constituting the seat and another part constituting the back of the chair, said web having one of its ends encompassing and loosely and removably attached to the top of said back portion, a rung arranged within the open front of said base, said web, intermediate its ends encompassing and loosely and removably attached to said rung, couplers extending into the outer ends of said horizontal parts for detachably connecting the base of said supporting element upon a support, and means extending through said horizontal parts, couplers and rung for detachably connecting the rung, couplers and web to the base portion of said supporting element, that part of said web forming the seat of the chair being provided with a cushion.

3. A portable chair comprising a frame-like supporting element formed of an open front and rear horizontal base portion and an upstanding open bottom and closed top back portion, a bendable web suspended in said portions having a part thereof constituting the seat of the chair and a part thereof constituting the back of the chair, said web being formed at one end with means for loosely and removably attaching it to the closed top of said back portion, a rung arranged in the open front of said base, said web formed intermediate its ends with means for loosely and removably attaching it to said rung, couplers extending into said supporting element and disposed in depending relation with respect to the open front of said base portion, and means extending through the sides of said element, said couplers and said rung for detachably connecting said couplers, rung and web to the front of the base portion of said element.

4. A portable chair comprising a frame-like supporting element formed of an open front and

4. A portable chair comprising a frame-like supporting element formed of an open front and

rear horizontal base portion and an upstanding open bottom and closed top back portion, a bendable web suspended in said portions having a part thereof constituting the seat of the chair and a part thereof constituting the back of the chair, said web being formed at one end with means for loosely and removably attaching it to the closed top of said back portion, a rung arranged in the open front of said base, said web formed intermediate its ends with means for loosely and removably attaching it to said rung, couplers extending into said supporting element and disposed in depending relation with respect to the open front of said base portion, and means extending through the sides of said element, said couplers and said rung for detachably connecting said couplers, rung and web to the front of the base portion of said element, that part of said web forming the seat of the chair having attached thereto a cushion.

5. In a portable seat for the purpose set forth, a frame-like supporting element having an open front base portion and closed top upstanding rear portion, a rung arranged in the open front of said base portion, a combined chair seat and chair back forming element suspended in said supporting element and loosely and removably connected respectively to said rung and to the top of said rear portion, spaced parallel upstanding couplers extending into said supporting element and disposed in depending relation with respect to the open front of said base portion, and means extending through said supporting element, said couplers and said rung for detachably connecting said couplers, rung and chair seat and chair back forming element to said supporting element. 30 35

6. In a portable seat for the purpose set forth, a frame-like supporting element having an open front base portion and closed top upstanding rear portion, a rung arranged in the open front of said base portion, a combined chair seat and chair back forming element suspended in said supporting element and loosely and removably connected respectively to said rung and to the top of said rear portion, spaced parallel upstanding couplers extending into said supporting element and disposed in depending relation with respect to the open front of said base portion, and means extending through said supporting element, said couplers and said rung for detachably connecting said couplers, rung and chair seat and chair back forming element to said supporting element, said rung being arranged relatively to said base portion to constitute a brace for the latter, and said means having parts thereof arranged relatively to said base portion to prevent the spreading of the base portion at its open front. 40 45 50 55

7. In a portable seat for the purpose set forth, a frame-like supporting element having an open front base portion and closed top upstanding rear portion, a rung arranged in the open front of said base portion, a combined chair seat and chair back forming element suspended in said supporting element and loosely and removably connected respectively to said rung and to the top of said rear portion, spaced parallel upstanding couplers extending into said supporting element and disposed in depending relation with respect to the open front of said base portion, and means extending through said supporting element, said couplers and said rung for detachably connecting said couplers, rung and chair seat and chair back forming element to said supporting element, and a cushion for said chair seat part, said cushion 60 65 70 75

ion being secured to and arranged within said combined chair seat and chair back forming element.

- 5 8. In a portable seat for the purpose set forth, a frame-like supporting element having an open front base portion and closed top upstanding rear portion, a rung arranged in the open front of said base portion, a combined chair seat and chair back forming element suspended in said supporting element and loosely and removably connected respectively to said rung and to the top of said rear portion, spaced parallel upstanding couplers extending into said supporting element and disposed in depending relation with respect to the
- 10

open front of said base portion, means extending through said supporting element, said couplers and said rung for detachably connecting said couplers, rung and chair seat and chair back forming element to said supporting element, said rung being arranged relatively to said base portion to constitute a brace for the latter, said means having parts thereof arranged relatively to said base portion to prevent the spreading of the base portion at its open front, and a cushion for said chair seat part, said cushion being secured to and arranged within said combined chair seat and chair back forming element.

CARL E. BOWLES.
